TRAIN CONTROL SYSTEM

Application filed November 6, 1923, Serial No. 672,088. Renewed July 18, 1932.

This invention relates to a train control system and more particularly to a system for controlling the movement of trains automatically by roadside mechanism and manually by the engineman on the train, and has special reference to the provision of a system in which automatic control is so combined with manual control as to assure absolute safety while permitting proper dispatch in the movement of trains.

One of the principal objects of our present invention comprehends the provision of a train control system in which train carried mechanism for governing the operation of the train is automatically controlled by roadside mechanism operable in accordance with roadside conditions in such a manner that the running operation of the train under unsafe traffic conditions is made dependent upon such traffic conditions only so as to provide absolute safety in train operation, and in which the cooperative control by the engineman is necessitated to supplement the automatic control for producing efficient and expeditious train movement.

In the production of an efficient train control system one of the factors of paramount importance is that of providing for the element of absolute safety of train movement under unsafe traffic conditions. To accomplish this it is requisite that a roadside mechanism reflecting the conditions on the roadside should assume unchallenged predominance in controlling the behaviour of the train under hazardous conditions, and that any condition of control impressed or imposed on an unsafely moving vehicle by the roadside mechanism should be beyond human interference. Another desideratum of infinite importance, however, is that of providing a system in which the engineman is restrained from shifting or casting the full burden of control upon the automatic train control mechanism, substitution of the automatic mechanism alone for the engineman being highly undesirable in practice. The ideal mode of controlling the movement of trains is that in which the engineman is compelled to be alert, or is deterred or restrained from being remiss in his duties so that proper

handling of the train is enforced and in which the engineman is supplanted by the automatic control mechanism only upon his failure to properly discharge his duties, and in which when so supplanted the automatic control is the dominant factor until safe running conditions of the train is resumed and the engineman again assumes control. When the engineman and the automatic train control mechanism are made to cooperate in this manner, the one acting as a check upon the other, absolute safety and proper dispatch in the running of trains is assured.

By our present invention to accomplish this object we provide a train control system in which full control of the train is left in the hands of the engineman so long as he is properly performing his duties in obedience to and in conformity with the indications of the roadside signalling apparatus, in which the control of the train is automatically taken from the engineman who is incapacitated or remiss in the performance of his duties and the train is automatically operated in accordance with roadside conditions, and in which the engineman is compelled to be alert and to again take charge of the operation of the train in order to avoid an undesirable condition of train control, the system thus combining the factor of absolute safety by making train operation dependent upon the automatic dictation of the roadside mechanism under hazardous conditions with the factor of proper train dispatching by making the efficient movement of the train dependent upon the activity and alertness of the engineman.

Another principal object of the present invention relates to the provision of a train control system in which the movement of the vehicle is controlled within the limits of two or three permissive speeds including a maximum speed beyond which the vehicle cannot run, a medium speed at or below which the vehicle must approach points of danger and run in localities where a greater speed would be unsafe, and a low speed above which the vehicle cannot run in "danger" localities, as in blocks occupied by other trains. In accomplishing this object of the invention, the design and construction of the system is such

that if a speed greater than the permissive maximum speed is attempted, the train is automatically controlled to cause a retardation of the speed of the vehicle and to preferably bring the same to a halt unless the engineman intervenes to modify the operation to permit the train to proceed at or below the maximum permissive speed after the speed of the vehicle is reduced to or below such maximum permissive speed; the system operating further so that if a speed greater than the medium permissive speed is attempted when roadside conditions require the movement of the vehicle at or below the medium speed, the train is automatically controlled in a similar manner to bring the same to a halt, the alertness of the engineman permitting, however, the placing of the train under the control of the medium permissive speed; and if a speed greater than the low permissive speed is attempted when the roadside conditions require a low speed restriction on the train, the train is automatically controlled to bring the same to a halt unless the engineman again modifies the automatic operation to place the train under the control of the low permissive speed.

To the accomplishment of the foregoing and such other objects as may hereinafter appear, our invention consists in the elements and their relation one to the other, as hereinafter particularly described and sought to be defined in the claims, reference being had to the accompanying drawings showing the preferred embodiment of our invention, and in which:

Fig. 1 is a diagrammatic view showing the vehicle carried apparatus and circuits and part of the roadside apparatus cooperating therewith, and

Fig. 2 is a diagrammatic view of a modification thereof.

In the train control system of our present invention, for directly controlling the movement of the train there is provided an electrically operated device for controlling the operation of the air brake system, the said device being under the control of cooperating train and roadside mechanism, and being operated thereby in accordance with roadside conditions. The electrically operated device comprises in the preferred construction an electromagnet 10 which controls the operation of a combined reservoir and brake valve of the type disclosed in the patent to A. G. Shaver No. 1,411,526 of April 4, 1922, and in the copending application of Allen B. Kendall Serial No. 443,046 of Feb. 7, 1921, the said reservoir and brake valve functioning upon the deenergization of the electromagnet 10 for cutting off the supply of air from the main reservoir of the air brake system to the engineman's brake valve and for opening the train pipe to exhaust, the electromagnet 10 being normally energized to hold open the

communication between the main reservoir and the engineman's brake valve and to close the train pipe to exhaust.

For directly controlling the operation of the electromagnet 10, there is provided a train carried circuit which is normally energized as under "clear" roadside conditions by a train carried source of energy such as the battery 11, the said circuit including the resistance r connected to the positive terminal of the battery, conductors 12 and 13, a movable make and break indicating means 14 which is operable in response to roadside conditions as will be detailed hereinafter to assume any one of the three positions a , b and c , the full-line inclined position a corresponding to the "normal" or "clear" position, the inclined dotted position b corresponding to one of the "non-clear" positions such as the "caution" position, and the vertical dotted line position c corresponding to another "non-clear" such as the "danger" position, the said circuit further including the conductors 15, 16 and 17, a contact mechanism 18, contact 19, conductors 20 and 21, the electromagnet 10, conductor 22 and conductor 23 connected to the negative terminal of the battery 11. Under "normal" or "clear" conditions with the indicating means 14 in the position a and with the contact mechanism 18 closed on the front contact 19, the brake controlling magnet is energized to permit the vehicle to proceed.

To place the train under the control of a maximum permissive speed, the electromagnet 10 instead of being controlled under "clear" conditions by the circuit traced above, may be controlled by an alternative circuit which is placed under the control of a speed circuit controller 24 which is operated in accordance with the speed of movement of the train. This alternative circuit is the same as that above described, with the exception that the conductor 12 is replaced by the conductor 25, the common contact 26, the contact 27 and the conductor 28, so that the electromagnet 10 in addition to being under the control of the make and break indicating means 14 and the contact mechanism 18 is also under the control of the speed controlled contact mechanism 24 at the contact 27. It will be apparent that with this construction when the speed of the train exceeds a predetermined maximum limit the circuit will be opened at the contact 27 and the electromagnet 10 deenergized.

In the operation of our system when a permissive speed is exceeded the electromagnet 10 is operated to bring the vehicle to a halt, the deenergization of this magnet persisting regardless of the subsequent decrease of speed of the vehicle unless the engineman is alert and intervenes to modify the operation of the magnet, modification being however permissible only when the vehicle

reaches a speed which is considered safe under the particular traffic conditions then existing.

In accord with this operation, when the maximum speed becomes operative to de-energize the electromagnet 10, the deenergization will persist until the manual modification by the engineman. To this end the contact mechanism 18, 19 is provided, this contact mechanism comprising a stick contact under the control of a relay 29 which is connected in parallel with the electromagnet 10 to the conductors 21 and 22 by means of the conductors 30, 31 and 32. With this construction it will be seen that when the electromagnet 10 is energized the stick relay 29 is energized to maintain or hold the contact 18 in engagement with the front contact 19 and when the electromagnet 10 is deenergized the relay 29 will be deenergized to permit the opening of the contact 18, the opening of this contact maintaining open the normal or maximum speed control circuit above traced regardless of the subsequent closing of this circuit at the contact 27 in response to a decrease of speed of the train. To modify the operation of the electromagnet 10 and forestall a "stop" of the train after the speed of the train has been reduced to or below the maximum permissive speed, we provide a circuit controlling means 33 manually operable by the engineman for closing the contact mechanism 18, the said circuit controlling means being preferably of the type disclosed in the application of A. G. Shaver Serial No. 634,053 of April 23, 1923, the said circuit controlling means generally comprising a stem part 34 coacting with the contact mechanism 18 and a push button part 35 manually manipulable by the engineman connected to the stem part 34 by means of a mechanism which comprises a fluid transmission means formed by providing a piston 34a at the lower end of the stem 34 loosely fitting the interior wall of the cylindrical vessel portion 35a of the push button 35, the said vessel containing a suitable fluid. With this construction it will be evident that when the push button is operated to an ascended position, the fluid will act against the piston to transmit the operation to the stem 34 to move the same to an ascended position and to actuate the contact mechanism to closing position, and that after such an operation has taken place the stem 34 under the influence of gravity or the like will return to descended position independently of the return of the push button device, the fluid gradually seeping through the clearance between the piston 34a and the wall of the vessel 35a, and the operation being such that the contact mechanism is actuated by a mechanical impulse to assume its upper position only momentarily and being free to move to descended position in the event that the circuit

is not in a condition to be energized. The condition automatically imposed upon the control circuit, as by the speed of the train exceeding the maximum permissive speed, is therefore maintained and cannot be cancelled by a premature operation of the manual push button; and it is therefore only when the train is reduced to the safe speed and in the present instance the maximum permissive speed, that the normal circuit controlling electromagnet 10 will be closed and maintained closed by the stick relay 29. Moreover, with this construction of the manual circuit controlling means the push button cannot be held by the engineman or operator in its ascended position so as to thwart or negative the operation of the automatic control mechanism, a single impulse operation being provided regardless or irrespective of the duration of operation of the push button device, the integrity of the control of the circuit by the speed circuit controller 24 and the indicating means 14 being thereby maintained.

For the purpose of informing the engineman when the train has been brought to or below the predetermined speed to permit of modifying the operation of the electromagnet 10, we provide a signalling means which may comprise a lamp 36 connected to the conductor 32 by means of the conductor 37 and connected to a back contact 38 by means of the conductor 39. With this circuit construction it will be seen that when the contact mechanism 18 is released by the deenergization of the relay 29, the contact mechanism will close on its back contact 38 and when the speed of the train has been reduced to the permissive speed so that the speed controlled contact 27 is closed, the lamp 36 will be illuminated, (informing the engineman that operation of the push key will effect reenergization of the electromagnet) by means of the circuit comprising the resistance r , conductor 25, contacts 26 and 27, conductors 28 and 13, indicating means 14, conductors 15, 16 and 17, contact mechanism 18, back contact 38, conductor 39, lamp 36, and conductors 37, 32 and 23.

With the system thus far described, therefore, under "clear" running conditions the vehicle may proceed at an unlimited speed or in the alternative at a speed at or below a permissive maximum speed, and if the vehicle exceeds such permissive maximum speed the brake controlling magnet is operated to bring the vehicle to a "stop", this imposed "stop" condition being, however, modified by the engineman by operation of the push key 35 after the speed of the vehicle has been reduced to the safe predetermined maximum speed as indicated by the lamp 36, the modification consisting in again placing the brake controlling magnet 10 under the control of the maximum permissive speed of the vehicle.

For operating the brake controlling mag-

net 10 in response to and in accordance with roadside or traffic conditions, there is provided cooperating train and roadside mechanism which functions to cause the make and break 5 indicating means 14 to be operated selectively to the positions *a*, *b* and *c*. The train and roadside mechanism for controlling the action of the indicating means includes the provision of a roadside energy transmitting 10 means which in the present form of our invention comprises a plurality of ramp rails spaced along the roadside, a rail such as indicated at 40 being provided for each section or block of the track, the said ramp rail comprising 15 means for transmitting energy to a train carried shoe mechanism 41 under safe roadside conditions, such energy being transmitted to a translating device such as the indication selector generally designated as 42, 20 the action of which directly controls the operation of the make and break means 14. The indication selector 42 preferably comprises a unit such as is disclosed in the copending application of Theodore Bodde Serial No. 634- 25 059 filed April 23, 1923, the indication selector comprising a stator field magnet 43 and a rotor 44 movable into any of three positions, the normal position *a'*, the caution position *b'*, and the danger position *c'*, corresponding 30 to the positions *a*, *b* and *c* simultaneously assumed by the make and break means 14, which latter is operated by the indication selector, the position *a'* being produced by 35 energizing the magnet 43 with a current of a given polarity, the position *b'* being assumed by energizing the magnet 43 with a current of a reverse polarity, and the position *c'* being assumed when the magnet 43 is unenergized. The indication selector further includes a 40 locking device 45 controlled by an electromagnet 46 and operative for engaging a notch 47 in the rotor 44 to lock the same in the "neutral" or "danger" position.

The electromagnets 43 and 46 are arranged 45 in series and are connected in partial circuit to the shoe 41 and to the frame of the vehicle represented by the ground 48 by means of the conductors 49 and 50, the construction being such that when the shoe 41 moves in engagement with and over the ramp 40, the said partial circuit will cooperate with a roadside partial circuit (not shown) connected to the ramp 40 and to the rails, as is disclosed for example in the application of A. G. Shaver 55 292,548 filed May 25, 1919, the cooperation being such that under normal or "clear" roadside conditions the ramp 40 will be energized by current of a given polarity to correspondingly energize the magnet 43, and under an 60 "unclear" such as a "caution" roadside condition the ramp 40 will be energized with current of an opposite polarity to correspondingly energize the magnet 43, and under a "danger" roadside condition the ramp 40 65 will be deenergized so that the magnet 43 is

unenergized when the shoe moves over the ramp.

For holding or maintaining the rotor 44 of the indication selector and the make and break means 14 in the positions to which they are actuated when the shoe moves over the ramp, the indication selector includes a holding circuit which is broken when the shoe moves over the ramp to permit freedom of action of the moving parts in response to energization of the magnet 43 and which is closed when the shoe disengages the ramp, the said holding circuit comprising an electromagnet 51 having pole pieces 52 and 53 selectively operable for cooperating with the armature 54 of the rotor 44 to hold the same in either the positions *a'* or *b'*, the circuit further including the conductor 55, the contact elements 56 and 57 normally bridged by the conducting piece 58 movable with the shoe 41, conductor 59, resistance *r*, battery 11, conductor 23, conductor 60, contact elements 61 and 62 normally bridged by the conducting piece 63 also fixed to and movable with the shoe 41, and conductor 64. This circuit is normally closed and when the shoe engages the ramp is broken at the contacts 56 and 62 to deenergize the magnet 51 and permit operation of the rotor by the action of the electromagnet 43. When the shoe leaves the ramp this circuit is again closed for energizing the electromagnet 51 to hold the armature in its operated position.

For manually-automatically controlling the 100 brake controlling magnet 10 when the vehicle carried mechanism receives a "caution" indication, the make and break indicating means 14 controls a circuit which is under the control of the speed controller 24 and which is so operated that the train is placed under the control of a medium permissive speed such as for example a speed of 35 miles an hour, the said circuit comprising battery 11, resistance *r*, conductor 25, contact 26, a medium permissive speed contact 65, conductor 66, make and break means 14 in position *b*, conductors 15, 16 and 17, contact mechanism 18, contact 19, conductors 20 and 21, magnet 10 and conductors 22 and 23. With this described arrangement the system 105 is subject to the following operations:

A. If the vehicle passes into a "caution" block and the indication selector receives a "caution" indication, the make and break means 14 will move from the position *a* to the position *b*, breaking the normal controlling circuit for the magnet 10 and making the medium speed control circuit described above. The relay 29 is preferably a slow releasing relay so that the contact mechanism 18 is maintained in its front contact making position during the time of movement of the make and break means 14 from its "clear" to its "caution" position. If under these 110 conditions the speed of the train is at or below 115

the medium permissive speed, as when the engineman is operating the train in obedience to the roadside signalling system, the contact 65 of the medium speed control circuit will be closed and the circuit will be closed at all contacts to maintain the energization of the brake controlling magnet 10, the vehicle thus being able to pass a "caution" ramp without a train control operation;

10 B. When, however, the train receives a "caution" indication and the speed of the train exceeds the permissive medium speed, the medium speed control circuit although closed at the make and break means 14 is open at the speed controlled contact 65 and under these conditions the circuit will be opened at the stick relay contact 18 and the opening of the circuit will persist due to the deenergization of the relay magnet 29 regardless of the subsequent decrease of speed to or below the permissive medium speed so that the deenergization of the magnet 10 will persist to bring the vehicle to a halt unless the engineman is alert and intervenes to modify 25 the operation of the magnet 10 and bring the same again under the control of the speed of the train;

C. If the engineman is alert, the "stop" condition imposed upon the vehicle may be modified by his manual intervention provided the speed of the vehicle is reduced to the "safe" speed under "caution" conditions, namely, the medium permissive speed. When the permissive speed is reached the lamp 36 will be illuminated by the circuit comprising resistance r , conductor 25, contacts 26 and 65 bridged by the controller 24, conductor 66, the indicating means 14, conductors 15, 16 and 17, contact 18, back contact 38, conductor 39, lamp 36 and conductors 37, 32 and 23. It is then that the engineman will operate the release or push key 35 and the medium speed control circuit being closed at the make and break means 14 and the contact means 65, is now in a condition to be energized by the contact mechanism 18, which latter will be maintained in its contact making position by the reenergization of the relay 29 since the said relay is connected 50 in parallel with the magnet 10 in the medium speed control circuit.

For manually-automatically controlling the brake controlling magnet 10 when the vehicle receives a "danger" indication, there is provided a low permissive speed control circuit which may be brought manually into operation when the make and break means 14 is operated to assume the "danger" position c . Under such "danger" conditions the maximum and medium permissive speed circuits heretofore traced are open at the make and break means 14 and the following operations are obtainable:

A. If when the vehicle carried mechanism 65 receives a "danger" indication the vehicle is

moving at or below a permissive low speed such for example as 10 miles an hour, a low permissive speed control circuit is automatically substituted for either the maximum or medium speed control circuits so that the engineman need perform no manual act since under such conditions he is acting in full obedience to the roadside signalling system, the substituted low speed control circuit comprising battery 11, resistance r , conductor 25, common contact 26, speed controller 24, a low permissive speed contact 68, a conductor 69, either the conductor 70 or the contact means 71 which is closed at the two contact points 72 and 73 only when the make and break means 14 is in the "danger" position c , conductor 17, contact mechanism 18, contact 19, conductors 20 and 21, magnet 10, and conductors 22 and 23, the slow releasing stick relay 29 remaining energized in parallel with the magnet 10;

B. If, however, when the "danger" indication is received the speed of the vehicle exceeds the low permissive speed, this low permissive speed control circuit is open at contact 68 and both the magnets 10 and 29 are deenergized, the circuit persisting in open condition regardless of the subsequent decrease of speed of the train to or below the low permissive speed since the contact mechanism 18 will be maintained open at the stick contact, thus imposing a "stop" condition on the train unless the engineman is alert to modify the "stop" condition after the speed of the train has been reduced to the "safe" or low speed limit;

C. If the engineman is alert and the speed of the train has been reduced to or below the low permissive speed, the engineman will operate the push key 35 to close the low speed control circuit, to place the train under the control of the low permissive speed, the lamp 36 indicating to the engineman the appropriate time for operating the push key, the lamp being closed by a circuit similar to that heretofore traced but including the low permissive speed contact 68.

It may at times be desirable to enforce an acknowledgement by the engineman passing into a "danger" zone even though the speed of the train has been reduced to or below the low permissive speed, and to this end the system may include means for making the low speed control circuit manual-automatic instead of automatic, such a manual-automatic control being shown in the modified system depicted in Fig. 2 of the drawings. To accomplish the desired result the low speed control circuit is taken through a contact means which is opened and closed by ascending and descending movement of the shoe, the said circuit including the battery 11, the resistance r , the conductor 25, contact 26, speed controller 24, contact 68, conductor 69, conductor 75, contacts 76 and 77 normally bridged by the conducting piece 78 attached

to the shoe 41 and opened when the shoe engages the ramp 40, conductor 79, conductor 17, contact mechanism 18, contact 19, conductors 20 and 21, magnet 10, conductor 22, 5 and conductor 23. With this circuit even though the train is moving at or below the low speed with the closing of contact 68, the circuit will be opened by the rising of the shoe 41 for effecting the deenergization of 10 the circuit unless the "danger" indication received is acknowledged by the engineman by the operation of a low speed release key 80 normally open and closed into engagement with contact 81, the release key and contact 15 being in parallel with the shoe contacts 76 and 77. Thus when the shoe engages a "danger" ramp and the key 80 is closed, the prior state of operation of the magnet 10 will be maintained, but however if the key 80 is 20 not closed, the low speed control circuit will be automatically opened to bring the vehicle to a halt, this automatic operation being however modifiable by the operation of the push key 35 when the speed of the train is at or 25 assumes the low permissive speed limit. The system shown in Fig. 2 is otherwise similar to that shown in Fig. 1 with the exception that the maximum speed control circuit is absent therein, and similar parts are therefore designated by similar reference characters.

The use and operation of our speed control system will in the main be fully apparent from the above detailed description thereof. It will be further apparent that numerous changes and modifications may be made in the structure disclosed without departing from the spirit of the invention, defined in 35 the following claims.

40 We claim:

1. In a manual-automatic speed control system for vehicles, vehicle carried mechanism comprising an electro-responsive device for controlling the movement of the vehicle, 45 an indicating means operable in response to roadside conditions for producing a "clear" or "non-clear" indication, instrumentalities under the control of the speed of the train and of said indicating means for controlling 50 the operation of the said device so that when the indicating means is operated to a non-clear position and the speed of the vehicle is reduced from a speed above a permissive speed to a speed at or below the permissive speed prior to such operation of the indicating means to its non-clear position, the said device is not operated but is operated automatically when the vehicle exceeds the permissive speed and the indicating means is in 55 the non-clear position, the said instrumentalities persisting when so operating the device after the speed of the vehicle is reduced below the said permissive speed, and manual means for modifying such persisting operation of the device when the speed of the vehicle 60 is reduced to or below the said permissive speed and for placing the device under the control of the permissive speed of 65 the vehicle.

2. In a manual-automatic speed control system for vehicles, vehicle carried mechanism comprising an electro-responsive device for controlling the movement of the vehicle, an indicating means operable in response to roadside conditions for producing a "clear" or "non-clear" indication, instrumentalities under the control of the speed of the train and associated with said indicating means for controlling the operation of the said device so that when the indicating means is operated to a non-clear position and the speed of the vehicle is reduced from a speed above a permissive speed to a speed at or below the permissive speed prior to such operation of the indicating means to its non-clear position, the said device is not operated but is operated automatically when the vehicle exceeds the permissive speed and the indicating means is in the non-clear position, the said instrumentalities persisting when so operating the device after the speed of the vehicle is reduced below the said permissive speed, and manual means for modifying such persisting operation of the device when the speed of the vehicle has been reduced to or below the said permissive speed so as to permit the vehicle to proceed at or below said speed.

3. In a manual-automatic speed control system for vehicles, vehicle carried mechanism comprising an electro-responsive device for controlling the movement of the vehicle, an indicating means operable in response to roadside conditions for producing a "clear" or "non-clear" indication, instrumentalities under the control of the speed of the train and associated with said indicating means for controlling the operation of the said device so that when the indicating means is operated to a non-clear position and the speed of the vehicle is reduced from a speed above a permissive speed to a speed at or below the permissive speed prior to such operation of the indicating means to its non-clear position, the said device is not operated but is operated automatically when the vehicle exceeds the permissive speed and the indicating means is in the non-clear position, the said instrumentalities persisting when so operating the device after the speed of the vehicle is reduced below the said permissive speed, and manual means for modifying such persisting operation of the device without altering the operation of the indicating means when the speed of the vehicle has been reduced to or below the said permissive speed so as to permit the vehicle to proceed at or below said speed.

3. In a manual-automatic speed control system for vehicles, vehicle carried mechanism comprising an electro-responsive device for controlling the movement of the vehicle, an indicating means operable in response to roadside conditions for producing a "clear" or "non-clear" indication, instrumentalities under the control of the speed of the train and of said indicating means for controlling the operation of the said device so that when the indicating means is operated to a non-clear position and the speed of the vehicle is reduced from a speed above a permissive speed to a speed at or below the permissive speed prior to such operation of the indicating means to its non-clear position, the said device is not operated but is operated automatically when the vehicle exceeds the permissive speed and the indicating means is in the non-clear position, the said instrumentalities persisting when so operating the device after the speed of the vehicle is reduced below the said permissive speed, and manual means for modifying such persisting operation of the device when the speed of the vehicle has been reduced to or below the said permissive speed and for placing the device under the control of the permissive speed of the vehicle.

4. In a manual-automatic speed control system for vehicles, vehicle carried mechanism comprising a brake controlling magnet,

an indicating means operable in response to roadside conditions for producing a "clear" or "non-clear" indication, circuit means under the control of the speed of the train and 5 of said indicating means for controlling the operation of the said magnet so that when the indicating means is operated to a non-clear position and the speed of the vehicle is reduced from a speed above a permissive speed 10 to a speed at or below the permissive speed prior to such operation of the indicating means to its non-clear position, the said magnet is not operated but is operated automatically to bring the vehicle to a halt when the 15 vehicle exceeds the permissive speed and the indicating means is in the non-clear position, the said circuit means persisting when so operating the magnet after the speed of the vehicle is reduced below the said permissive speed, and manual means for modifying such 20 persisting operation of the magnet by placing the same under the control of the permissive speed when the speed of the vehicle has been reduced to or below the said permissive speed. 25

5. A manual-automatic speed control system for vehicles, comprising a vehicle carried electro-responsive device for controlling the movement of the vehicle, a vehicle carried indicating means, roadside means operable in response to roadside conditions for intermittently producing a "clear" or "non-clear" indication in said indicating means, instrumentalities on the vehicle under the 30 control of the speed of the train and of said indicating means for controlling the operation of the said device so that when the indicating means is operated to a non-clear position and the speed of the vehicle is reduced from a speed above a permissive speed to a 35 speed at or below the permissive speed prior to such operation of the indicating means to its non-clear position, the said device is not operated but is operated automatically when the vehicle exceeds the permissive speed and the indicating means is in the non-clear position, the said instrumentalities persisting when so operating the device after the speed of the vehicle is reduced below the said permissive speed, and vehicle carried manual 40 means for modifying such persisting operation of the device when the speed of the vehicle has been reduced to or below the said permissive speed so as to permit the vehicle to 45 proceed at or below said speed, said manual modifying means comprising mechanism operable when the permissive speed is again exceeded for producing a persisting operation of said device. 50

6. In a manual-automatic speed control system for vehicles, vehicle carried mechanism comprising an electro-responsive device for controlling the movement of the vehicle, an indicating means operable in response to 55 roadside conditions for producing a "clear" 60

or "non-clear" indication, a speed controlled means, instrumentalities under the control of the speed controlled means and of said indicating means for controlling the operation of the said device so that when the indicating means is operated to a non-clear position and the speed of the vehicle is reduced from a speed above a permissive speed to a speed at or below the permissive speed prior to such 70 operation of the indicating means to its non-clear position, the said device is not operated but is operated automatically when the vehicle exceeds the permissive speed and the indicating means is in the non-clear position, the said instrumentalities persisting when so operating the device after the speed of the train is reduced below the said permissive speed, and manual means for modifying such persisting operation of the device and for placing the same under the control of the speed controlled device when the speed of the train has been reduced to or below the said permissive speed. 80

7. In a manual-automatic train control system, vehicle carried mechanism comprising an electrically operated device, a make and break indicating means, a contact mechanism, circuit means connecting the said electrically operated device with so as to be controlled by both the make and break indicating means and the contact mechanism, means operable in accordance with roadside conditions for controlling the operation of the make and break means to open and close the same, means independent of said device operative upon the opening of the make and break means for automatically controlling the contact mechanism to open the same and maintain the same open regardless of the subsequent closing of the make and break device, and means for manually operating the contact mechanism to close the same and to permit behaviour of the same after a manual operation thereof independent of the manual operating means whereby an improper manual operation to nullify the automatic control of the contact mechanism is prevented and the integrity of the control of the circuit by both the make and break device and the contact mechanism maintained. 90

8. In a manual-automatic train control system, vehicle carried mechanism comprising an electrically operated device, a make and break indicating means, a contact mechanism, a normally closed circuit connecting the said electrically operated device with so as to be controlled by both the make and break means and the contact mechanism, means operable in accordance with roadside conditions for controlling the operation of the make and break means to open and close the same, means independent of said device operative upon the opening of the make and break means for automatically controlling the contact mechanism to open the same and main- 95 100 105 110 115 120 125 130

tain the same open regardless of the subsequent closing of the make and break means, and means for manually controlling the contact mechanism operative to close the same.

5 9. In a manual-automatic train control system, vehicle carried mechanism comprising an electrically operated device, a speed controlled contact mechanism, a second contact mechanism, a make and break means, 10 circuit means connecting the electrically operated device with so as to be controlled combinedly by the contact mechanisms and the make and break means, means operable in accordance with roadside conditions for controlling the operation of the make and break means to open and close the same, means operative upon the opening of the speed controlled contact mechanism or the opening 15 of the make and break means for automatically controlling the second contact mechanism to open the same and maintain the same open regardless of the subsequent closing of either the speed controlled contact mechanism or the make and break means and means 20 for manually closing the second contact mechanism.

10. In a manual-automatic train control system, vehicle carried mechanism comprising an electrically operated device, a speed controlled contact mechanism, a second contact mechanism, a make and break means, a 30 circuit means connecting the electrically operated device with so as to be controlled combinedly by the contact mechanisms and the make and break means, means operable in accordance with roadside conditions for controlling the operation of the make and break means to open and close the same, means operative upon the opening of the speed controlled contact mechanism or the opening of 35 the make and break means for automatically controlling the second contact mechanism to open the same and maintain the same open regardless of the subsequent closing of either the speed controlled contact mechanism or the make and break means, and means for manually operating the second contact mechanism to close the same and to permit behaviour of the same after a manual operation thereof independent of its manual operating means whereby an improper manual operation to nullify the automatic control of the second 40 contact mechanism is prevented.

45 11. In a train control system, vehicle carried mechanism comprising an electrically operated device, a speed controlled contact mechanism, a second contact mechanism, a make and break means, circuit means connecting the electrically operated device with 50 so as to be controlled combinedly by the contact mechanisms and the make and break means, means operable in accordance with roadside conditions for controlling the operation of the make and break means to open and 55 close the same, means operative upon the

opening of the speed controlled contact mechanism for opening the second contact mechanism and maintaining the same open regardless of the subsequent closing of the speed controlled contact mechanism, and means for manually closing the second contact mechanism. 70

12. In a train control system, vehicle carried mechanism comprising an electrically operated device, a speed controlled contact mechanism, a second contact mechanism, a make and break means, circuit means connecting the electrically operated device with so as to be controlled combinedly by the contact mechanisms and the make and break means, means operable in accordance with roadside conditions for controlling the operation of the make and break means, means operative upon the opening of the speed controlled contact mechanism for automatically controlling the 80 second contact mechanism to open the same and maintain the same open regardless of the subsequent closing of the speed controlled contact mechanism, and means for manually operating the second contact mechanism to 85 close the same and to permit behaviour of the same after a manual operation thereof, independent of the manual operating means whereby an improper manual operation to nullify the automatic control of the second 90 contact mechanism is prevented.

13. In a manual-automatic speed control system for vehicles, vehicle carried mechanism comprising an electrically operated device, a make and break indicating means 100 operable into a "clear" or "non-clear" position, a speed controlled contact mechanism, a normally operative circuit for the device controlled by the indicating means in clear position, a second and normally inoperative circuit for the device controlled by the contact mechanism and the make and break indicating means in non-clear position, the second circuit being operable so that when the indicating means is operated from its clear to 105 its non-clear position and the speed of the vehicle is reduced from a speed above a permissive speed to a speed at or below the permissive speed prior to such operation of the indicating means to its non-clear position, the normal operation of the said device is maintained but the said device is operated automatically to bring the vehicle to a halt when 110 the vehicle exceeds the permissive speed and the indicating means is in the non-clear position, the said second circuit persisting when the device is so operated to bring the vehicle to a halt after the speed of the vehicle is reduced below the said permissive speed, and manual means for modifying the persisting operation of the second circuit when the speed of the vehicle has been reduced to or below 115 the said permissive speed so as to permit the vehicle to proceed at or below said speed. 120

125 130

14. In a manual-automatic speed control system for vehicles, vehicle carried mechanism comprising an electrically operated device, a make and break indicating means operable into a "clear" or "non-clear" position, a speed controlled contact mechanism, a normally closed circuit for the device controlled by the indicating means in clear position, a second and normally open circuit for the device controlled by the contact mechanism and the make and break indicating means in non-clear position, the second circuit being operable so that when the indicating means is operated from its clear to its non-clear position and the speed of the vehicle is reduced from a speed above a permissive speed to a speed at or below the permissive speed prior to such operation of the indicating means to its non-clear position, the second circuit is closed to maintain the normal operation of the said device but when the vehicle exceeds the permissive speed and the indicating means is in the non-clear position the said second circuit is opened and persists opened after the speed of the vehicle is reduced below the said permissive speed, and manually operated means for modifying the persisting operation of the second circuit when the speed of the vehicle has been reduced to or below the said permissive speed so as to permit the vehicle to proceed at or below said speed.

15. In a manual-automatic speed control system for vehicles, vehicle carried mechanism comprising a magnet, a make and break indicating means operable into a "clear" or "non-clear" position, a speed controlled contact mechanism, a normally closed circuit for the magnet controlled by the indicating means in clear position, a second and normally open circuit for the magnet controlled by the contact mechanism and the make and break indicating means in non-clear position, the second circuit being operable so that when the indicating means is operated from its clear to its non-clear position and the speed of the vehicle is reduced from a speed above a permissive speed to a speed at or below the permissive speed prior to such operation of the indicating means to its non-clear position, the normal energization of the magnet is maintained but the said magnet is automatically deenergized when the vehicle exceeds the permissive speed and the indicating means is in the non-clear position, the said second circuit persisting when the magnet is so deenergized after the speed of the vehicle is reduced below the said permissive speed, and manually operated means for modifying the persisting operation of the second circuit when the speed of the vehicle has been reduced to or below the said permissive speed so as to permit the vehicle to proceed at or below said speed.

16. A manual-automatic speed control system for vehicles comprising vehicle carried

mechanism including an electrically operated device, a make and break indicating means operable into a "clear" or "non-clear" position, a speed controlled contact mechanism, a normally operative circuit for the device controlled by the indicating means in clear position, a second and normally inoperative circuit for the device controlled by the contact mechanism and the make and break indicating means in non-clear position, the second circuit being operable so that when the indicating means is operated from its clear to its non-clear position and the speed of the vehicle is reduced from a speed above a permissive speed to a speed at or below the permissive speed prior to such operation of the indicating means to its non-clear position, the normal operation of the said device is maintained but the said device is operated automatically to bring the vehicle to a halt when the vehicle exceeds the permissive speed and the indicating means is in the non-clear position, the said second circuit persisting when the device is so operated to bring the vehicle to a halt after the speed of the vehicle is reduced below the said permissive speed, manual means for modifying the persisting operation of the second circuit when the speed of the vehicle has been reduced to or below the said permissive speed so as to permit the vehicle to proceed at or below said speed, and roadside mechanism for intermittently operating the indicating means to its "clear" or "non-clear" position in accordance with roadside conditions.

17. In a manual-automatic speed control system for vehicles, vehicle carried mechanism comprising an electrically operated device, a make and break indicating means operable into a "clear" or "non-clear" position, a contact mechanism, a speed controlled contact mechanism, a normally operative circuit connecting the device, the contact mechanism and the make and break indicating means, a second and normally inoperative circuit for the device connecting the contact mechanism, the speed controlled contact mechanism, and the make and break indicating means operable so that when the indicating means is operated to its non-clear position and the speed of the vehicle is reduced from a speed above a permissive speed to a speed at or below the permissive speed prior to such operation of the indicating means to its non-clear position, the normal operation of the said device is maintained but the said device is operated automatically to bring the vehicle to a halt when the vehicle exceeds the permissive speed and the indicating means is in the non-clear position, the said second circuit persisting when the device is so operated to bring the vehicle to a halt after the speed of the vehicle is reduced below the said permissive speed, and manually operated means for modifying the persisting operation of the second circuit when the speed of the vehicle has been reduced to or below the said permissive speed so as to permit the vehicle to proceed at or below said speed.

circuit when the speed of the vehicle has been reduced to or below the said permissive speed so as to permit the vehicle to proceed at or below said speed.

18. In a manual-automatic speed control system for vehicles, vehicle carried mechanism comprising an electrically operated device, a make and break indicating means operable into a "clear" or "non-clear" position, a contact mechanism, a speed controlled contact mechanism, a normally operative circuit connecting the device, the contact mechanism and the make and break indicating means, means including a second and normally inoperative circuit for the device connecting the contact mechanism, the speed controlled contact mechanism, and the make and break indicating means operable so that when the indicating means is operated to its non-clear position and the speed of the vehicle is reduced from a speed above a permissive speed to a speed at or below the permissive speed prior to such operation of the indicating means to its non-clear position, the normal operation of the said device is maintained but the said device is operated automatically to bring the vehicle to a halt when the vehicle exceeds the permissive speed and the indicating means is in the non-clear position, the said second circuit persisting when the device is so operated to bring the vehicle to a halt after the speed of the vehicle is reduced below the said permissive speed, and manually operated means for modifying the persisting operation of the second circuit for placing the same under the control of the speed controller contact mechanism when the speed of the vehicle has been reduced to or below the said permissive speed so as to permit the vehicle to proceed at or below said speed.

19. In a manual-automatic train control system, vehicle carried mechanism comprising an electrically operated device, a speed controlled contact mechanism, a stick relay contact mechanism, a make and break means, circuit means connecting the electrically operated device with so as to be controlled combinedly by the contact mechanisms and the make and break means, means operable in accordance with roadside conditions for controlling the operation of the make and break means to open and close the same, said circuit means being such that upon opening of the speed controlled contact mechanism the circuit means will be opened and maintained open at the stick relay contact mechanism regardless of the subsequent closing of the speed controlled contact mechanism, and means for manually closing the stick relay contact mechanism.

20. In a manual-automatic train control system, vehicle carried mechanism comprising an electrically operated device, a speed controlled contact mechanism, a stick relay contact mechanism, a make and break means,

circuit means connecting the electrically operated device with so as to be controlled combinedly by the contact mechanisms and the make and break means, means operable in accordance with roadside conditions for controlling the operation of the make and break means to open and close the same, said circuit means being such that upon opening of the speed controlled contact mechanism the circuit means will be opened and maintained open at the stick relay contact mechanism regardless of the subsequent closing of the speed controlled contact mechanism, and means for manually operating the stick relay contact mechanism to close the same and to permit behaviour of the same after a manual operation independent of the manual operating means whereby an improper manual operation to nullify the automatic control of the stick relay contact mechanism is prevented.

21. In a manual-automatic train control system, vehicle carried mechanism comprising an electrically operated device, a speed controlled contact mechanism, a stick relay contact mechanism, a make and break means circuit means connecting the electrically operated device with so as to be controlled combinedly by the contact mechanisms and the make and break means, means operable in accordance with roadside conditions for controlling the operation of the make and break means to open and close the same, said circuit means being such that upon opening of the speed controlled contact mechanism the circuit means will be opened and maintained open at the stick relay contact mechanism regardless of the subsequent closing of the speed controlled contact mechanism, means for manually closing the stick relay contact mechanism, and a signalling means for indicating when the said second contact mechanism is opened and the speed controlled contact mechanism is closed.

22. In a manual-automatic speed control system for vehicles, vehicle carried mechanism comprising a device for controlling the movement of the vehicle, an indicating means operable in accordance with roadside conditions for indicating "clear", "caution" and "danger" conditions, means for operating the device to permit movement of the vehicle above a medium permissive speed when the indicating means indicates "clear", means operable when the indicating means changes from "clear" to "caution" and the speed of the vehicle exceeds the medium permissive speed for automatically operating said device to bring the vehicle to a halt, this operation of the device persisting regardless of the subsequent decrease of speed below the medium permissive speed, means operable when the indicating means changes from "clear" or "caution" to "danger" and the

speed of the vehicle exceeds a low permissive speed for operating the said device to bring the vehicle to a halt, this latter operation of the device persisting regardless of the subsequent decrease of the speed below the low permissive speed, and manually operable means for modifying the operation of the device to permit the vehicle to proceed at or below the medium permissive speed when the speed is reduced to the medium permissive speed under a "danger" indicating condition.

23. In a manual-automatic speed control system for vehicles, vehicle carried mechanism comprising a device for controlling the movement of the vehicle, an indicating means operable in accordance with roadside conditions for indicating "clear", "caution" and "danger" conditions, means for operating the device to permit movement of the vehicle above a medium permissive speed when the indicating means indicates "clear", means operable when the indicating means changes from "clear" to "caution" and the speed of the vehicle exceeds the medium permissive speed for automatically operating said device to change the speed of the vehicle, this operation of the device persisting regardless of the subsequent decrease of speed below the medium permissive speed, means operable when the indicating means changes from "caution" to "danger" and the speed of the vehicle exceeds a low permissive speed for operating the said device to change the speed of the vehicle, this latter operation of the device persisting regardless of the subsequent decrease of the speed below the low permissive speed, and manually operable means for modifying the operation of the device to permit the vehicle to proceed at or below the medium permissive speed when the speed is reduced to the medium permissive speed under a "danger" indicating condition.

24. In a manual-automatic speed control system for vehicles, vehicle carried mechanism comprising a device for controlling the movement of the vehicle, an indicating means operable in accordance with roadside conditions for indicating "clear", "caution" and "danger" conditions, means for operating the device to permit movement of the vehicle above a medium permissive speed when the indicating means indicates "clear", means operable when the indicating means changes from "clear" to "caution" and the speed of the vehicle exceeds the medium permissive speed for automatically operating said device to bring the vehicle to a halt, this opera-

tion of the device persisting regardless of the subsequent decrease of speed below the medium permissive speed, means operable when the indicating means changes from "clear" or "caution" to "danger" and the speed of the vehicle exceeds a low permissive speed for operating the said device to bring the vehicle to a halt, this latter operation of the device persisting regardless of the subsequent decrease of the speed below the low permissive speed, manually operable means for modifying the operation of the device to permit the vehicle to proceed at or below the medium permissive speed when the speed is reduced to the medium permissive speed under a "danger" indicating condition, and intermittent roadside mechanism for operating said indicating means in accordance with traffic conditions.

25. In a manual-automatic speed control system for vehicles, vehicle carried mechanism comprising a device for controlling the movement of the vehicle, an indicating means operable in accordance with roadside conditions for indicating "clear", "caution" and "danger" conditions, means for operating the device to permit normal movement of the vehicle above a medium permissive speed when the indicating means indicates "clear", means operable when the indicating means changes from "clear" to "caution" and the speed of the vehicle is at or below the medium permissive speed to maintain the normal operation of the device but when the vehicle exceeds the medium permissive speed for automatically operating said device to change the speed of the vehicle, this operation of the device persisting regardless of the subsequent decrease of speed below the medium permissive speed, means operable when the indicating means changes from "clear" or "caution" to "danger" and the speed of the vehicle is at or below a low permissive speed to maintain the prior state of operation of the device but when the vehicle exceeds the low permissive speed for operating the said device to change the speed of the vehicle, this latter operation of the device persisting regardless of the subsequent decrease of the speed below the low permissive speed, and manually operable means for modifying the operation of the device to permit the vehicle to proceed at or below the medium permissive speed when the speed is reduced to the medium permissive speed under a "danger" indicating condition.

26. In a manual-automatic speed control system for vehicles, vehicle carried mechanism comprising a device for controlling the movement of the vehicle, an indicating means operable in accordance with roadside conditions for indicating "clear", "caution" and "danger" conditions, means for operating the device to permit movement of the vehicle above a medium permissive speed when the indicating means indicates "clear", means operable when the indicating means changes from "clear" to "caution" and the speed of the vehicle exceeds the medium permissive speed for automatically operating said device to bring the vehicle to a halt, this opera-

26. In a manual-automatic speed control system for vehicles, vehicle carried mechanism comprising a device for controlling the movement of the vehicle, an indicating means operable in accordance with roadside conditions for indicating "clear", "caution" and "danger" conditions, means for operating the device to permit movement of the vehicle above a medium permissive speed when the indicating means indicates "clear", means operable when the indicating means changes from "clear" to "caution" and the speed of the vehicle exceeds the medium permissive speed for automatically operating said device to bring the vehicle to a halt, this operation of the device persisting regardless of the subsequent decrease of speed below the medium permissive speed, means operable when the indicating means changes from "clear" or "caution" to "danger" and the speed of the vehicle exceeds a low permissive speed for operating the said device to bring the vehicle to a halt, this latter operation of the device persisting regardless of the subsequent decrease of the speed below the low permissive speed, and unitary manually operable means for modifying the operation of the device to permit the vehicle to proceed at or below the medium permissive speed when the speed is reduced to the medium permissive speed under a "caution" indicating condition and to permit the vehicle to proceed at or below the low permissive speed when the speed is reduced to said low permissive speed under a "danger" indicating condition.

27. In a manual-automatic speed control system for vehicles, vehicle carried mechanism comprising an electro-responsive device for controlling the movement of the vehicle, an indicating means operable in accordance with roadside conditions for indicating "clear" and "non-clear" conditions, means for operating the device to permit normal movement of the vehicle above a given permissive speed when the indicating means indicates "clear", means operable when the indicating means changes from "clear" to "non-clear" and the speed of the vehicle is at or below the given permissive speed for maintaining the normal operation of the device but when the vehicle exceeds the given permissive speed when the indicating means is so changed for automatically operating said device to change the speed of the vehicle, this operation of the device persisting regardless of the subsequent decrease of speed below the given permissive speed, and manually operable means for modifying such latter operation of the device so as to permit the vehicle to proceed at or below the said permissive speed when the speed of the vehicle is reduced to such speed.

28. In a manual-automatic speed control system for vehicles, vehicle carried mecha-

nism comprising an electro-responsive device for controlling the movement of the vehicle, and indicating means operable in accordance with roadside conditions for indicating "clear" and "caution" conditions, means for operating the device to permit normal movement of the vehicle above a medium permissive speed when the indicating means indicates "clear", means operable when the indicating means changes from "clear" to "non-clear" and the speed of the vehicle is at or below the medium permissive speed for maintaining the normal operation of the device but when the vehicle exceeds the medium permissive speed when the indicating means is so changed for automatically operating said device to bring the vehicle to a halt, this operation of the device persisting regardless of the subsequent decrease of speed below the medium permissive speed, and manually operable means for modifying the operation of the device to permit the vehicle to proceed at or below the said permissive speed when the speed of the vehicle is reduced to such speed.

29. In a manual-automatic speed control system for vehicles, vehicle carried mechanism comprising an electro-responsive device for controlling the movement of the vehicle, an indicating means operable in accordance with roadside conditions for indicating "caution" and "danger" conditions, means for operating the device to permit movement of the vehicle at or below a medium permissive speed when the indicating means indicates "caution", means operable when the indicating means changes from "caution" to "danger" and the speed of the vehicle is at or below a low permissive speed for maintaining the medium speed operation of the device but when the vehicle exceeds the low permissive speed when the indicating means is so changed for automatically operating the device to change the speed of the vehicle, this operation of the device persisting regardless of the subsequent decrease of speed below the low permissive speed, and manually operable means for modifying the operation of the device when the speed of the vehicle is automatically changed to permit the vehicle to proceed at or below the low permissive speed after the vehicle speed is reduced to or below the low permissive speed.

30. In a manual-automatic speed control system for vehicles, vehicle carried mechanism comprising an electro-responsive device for controlling the movement of the vehicle, an indicating means operable in accordance with roadside conditions for indicating "caution" and "danger" conditions, means for operating the device to permit movement of the vehicle when the indicating means indicates "caution", means operable when the indicating means changes from "caution" to "danger" and the speed of the vehicle is at or below a low permissive speed

to maintain the prior state of operation of the device but when the vehicle exceeds the low permissive speed for automatically operating the device to bring the vehicle to a halt, this 5 latter operation of the device persisting regardless of the subsequent decrease of speed below the low permissive speed, and manually operable means for modifying the operation of the device when the speed of the vehicle 10 is automatically changed to permit the vehicle to proceed at or below the low permissive speed after the vehicle speed is reduced to or below the low permissive speed.

31. In a manual-automatic speed control system for vehicles, vehicle carried mechanism comprising a device for controlling the movement of the vehicle, an indicating means operable in accordance with roadside conditions for indicating "clear", "caution" and 20 "danger" conditions, means for operating the device to permit movement of the vehicle above a medium permissive speed and below a maximum permissive speed when the indicating means indicates "clear", means operable 25 when the indicating means changes from "clear" to "caution" and the speed of the vehicle exceeds the medium permissive speed for automatically operating said device to change the speed of the vehicle, this operation 30 of the device persisting regardless of the subsequent decrease of speed below the medium permissive speed, means operable when the indicating means changes from "caution" to "danger" and the speed of the vehicle exceeds a low permissive speed for operating the said device to change the speed of the vehicle, this latter operation of the device persisting regardless of the subsequent decrease of speed below the low permissive speed, 35 and manually operable means for modifying the operation of the device to permit the vehicle to proceed at or below the medium permissive speed when the speed is reduced to the medium permissive speed under a "caution" indicating condition and to permit the vehicle to proceed at or below the low permissive speed when the speed is reduced to said low permissive speed under a "danger" indicating condition.

50 32. In a manual-automatic speed control system for vehicles, vehicle carried mechanism comprising a device for controlling the movement of the vehicle, an indicating means operable in accordance with roadside conditions for indicating "clear", "caution" and "danger" conditions, means for operating the device to permit movement of the vehicle above a medium permissive speed and below a maximum permissive speed when the indicating means indicates "clear", and for operating the said device to bring the vehicle to a halt when the maximum permissive speed is exceeded under such "clear" indicating conditions, this operation of the device persisting regardless of the subsequent decrease

of speed below the maximum permissive speed, means operable when the indicating means changes from "clear" to "caution" and the speed of the vehicle exceeds the medium permissive speed for automatically operating said device to bring the vehicle to a halt, this operation of the device persisting regardless of the subsequent decrease of the speed below the medium permissive speed, means operable when the indicating means changes from "caution" to "danger" and the speed of the vehicle exceeds a low permissive speed, for operating the said device to bring the vehicle to a halt, this last operation of the device persisting regardless of the subsequent decrease of the speed below the low permissive speed, and manually operable means for modifying the operation of the device to permit the vehicle to proceed at or below the maximum permissive speed when the speed is reduced to the maximum speed under a "clear" indicating condition, and to permit the vehicle to proceed at or below the medium permissive speed when the speed is reduced to such medium permissive speed under a "caution" indicating condition, and to further permit the vehicle to proceed at or below the low permissive speed when the speed is reduced to said low permissive speed under a "danger" indicating condition.

33. In a manual-automatic speed control system for vehicles, vehicle carried mechanism comprising a device for controlling the movement of the vehicle, an indicating means operable in accordance with roadside conditions for indicating a "safe" and "unsafe" condition, means operable when the indicating means changes from "safe" to "unsafe" and the speed of the vehicle is at or below a permissive speed for maintaining the prior state of operation of the device if the engineman acknowledges the change of indication and to automatically operate the said device to bring the vehicle to a halt if the vehicle exceeds the permissive speed, and means for manually modifying the automatic operation of the device to permit the vehicle to proceed at or below the permissive speed, said manual modifying means being effective as soon as the vehicle is reduced to or below the permissive speed.

55 34. In a manual-automatic speed control system for vehicles, vehicle carried mechanism comprising a device for controlling the movement of the vehicle, an indicating means operable in accordance with roadside conditions for indicating a "caution" and "danger" condition, means operable when the indicating means changes from "caution" to "danger" and the speed of the vehicle is at or below a low permissive speed for maintaining the prior state of operation of the device if the engineman acknowledges the change of indication and to automatically operate the said device to bring the vehicle to a halt if the

vehicle exceeds the low permissive speed, and means for manually modifying the automatic operation of the device to permit the vehicle to proceed at or below the low permissive speed, said manual modifying means being effective as soon as the vehicle is reduced to or below the low permissive speed.

35. A manual-automatic speed control system for vehicles, comprising a vehicle carried electrically operable device for controlling the movement of the vehicle, a vehicle carried indicating means operable in accordance with roadside conditions for indicating a "safe" and "unsafe" condition, roadside means intermittently controlling the said indicating means, electrical circuit means operable when the indicating means is operated under "unsafe" roadside conditions and the speed of the vehicle is at or below a permissive speed for maintaining the prior state of operation of the device if the engineman acknowledges the operation of the indicating means and to automatically operate the said device to bring the vehicle to a halt if the vehicle exceeds the permissive speed, and means for manually modifying the automatic operation of the device to permit the vehicle to proceed at or below the permissive speed, said manual modifying means being effective as soon as the vehicle is reduced to or below the permissive speed.

36. A manual automatic speed control system for vehicles, comprising a vehicle carried device for controlling the movement of the vehicle, an indicating means on the vehicle, cooperative vehicle carried and roadside mechanism including roadside means spaced at intervals at controlling stations intermittently operable in accordance with roadside conditions for producing a "safe" and "unsafe" indication in said indicating means, means operable when the vehicle carried mechanism passes an "unsafe" indicating roadside means for automatically operating the device to bring the vehicle to a halt irrespective of the speed of the vehicle, means operable by the engineman for preventing such operation of the device if the vehicle is moving at or below a permissive speed, and means manually operable by the engineman after the device is automatically operated when the vehicle exceeds the permissive speed for modifying the operation of the device after the speed is reduced to the permissive speed to permit the vehicle to move at or below such permissive speed.

37. A manual-automatic speed control system for vehicles, comprising a vehicle carried device for controlling the movement of the vehicle, an indicating means on the vehicle, cooperative vehicle carried and roadside mechanism including roadside means spaced at intervals at controlling stations intermittently operable in accordance with roadside conditions for producing a "safe" and "un-

safe" indication in said indicating means, means operable when the vehicle carried mechanism passes an unsafe indicating roadside means for automatically operating the device to bring the vehicle to a halt irrespective of the speed of the vehicle and means operable by the engineman for preventing such operation of the device if the vehicle is moving at or below a permissive speed and for modifying such operation of the device when the vehicle exceeds the permissive speed after the speed is reduced to the permissive speed to permit the vehicle to move at or below such permissive speed.

38. A manual-automatic speed control system for vehicles, comprising a vehicle carried device for controlling the movement of the vehicle, an indicating means on the vehicle, cooperative vehicle carried and roadside mechanism including roadside means spaced at intervals at controlling stations intermittently operable in accordance with roadside conditions for producing a "caution" and "danger" indication in said indicating means, means operable when the vehicle carried mechanism passes a "danger" indicating roadside means for automatically operating the device to bring the vehicle to a halt irrespective of the change of speed of the vehicle, means operable by the engineman for preventing such operation of the device if the vehicle is moving at or below a low permissive speed, and means manually operable by the engineman after the device is so automatically operated when the vehicle exceeds the low permissive speed for modifying the operation of the device after the speed is reduced to the low permissive speed to permit the vehicle to move at or below such low permissive speed.
